UNITED STATES PATENT OFFICE.

EDWARD E. GOLD, OF NEW YORK, N. Y.

ELECTRIC HEATER.

No. 850,924.

Specification of Letters Patent.

Patented April 23, 1907.

Application filed May 4, 1906. Serial No. 315,146.

To all whom it may concern:

Be it known that I, EDWARD E. GOLD, a citizen of the United States, residing in the borough of Manhattan, city, county, and 5 State of New York, have invented certain new and useful Improvements in Electric Heaters, of which the following is a specification.

My invention aims to provide certain improvements designed for covering and protecting the connections between the wires of electric heaters and the mains. For this purpose I provide an electric car-heater having a chamber which constitutes a junction- 10 box for inclosing the ends of the line-wires leading into the heater. The wall of the junction-box is preferably provided with a socket which receives the end of a conduit inclosing the line-wire, so that the wire is entirely inclosed throughout the car, increasing 15 greatly the protection against fire and improving the appearance.

The accompanying drawings illustrate applications of the invention to a variety of 20 heaters.

Figure 1 shows in plan a pair of Gold standard electric heaters arranged under car-seats of a car. Fig. 2 is an end elevation of one of such heaters in position, the heater shown 25 being supposed to be at the end of the car. Fig. 3 is a horizontal section through one of the heaters and the junction-box. Fig. 4 is a horizontal section of the same at a lower point. Fig. 5 is a side elevation of one of the junction-boxes. Fig. 6 is an end elevation 30 of the box. Fig. 7 is a plan of a pair of heaters with a common junction-box. Fig. 8 is a horizontal section through such junction-box. Fig. 9 is a rear view of a style of heater 35 adapted for attachment to the risers of longitudinal car-seats. Fig. 10 is a plan thereof, showing the riser in section. Figs. 11 and 12 are similar views with the heaters so close together that the junction-box extends from 40 one heater to the next without the interposition of any other conduit. Fig. 13 is a vertical section of a truss-plank heater of the type adapted for attachment to the truss-plank of the car. Fig. 14 is a horizontal section 45 of the same. Fig. 15 is in part a front elevation and in part a vertical longitudinal section of the same.

The junction-boxes are all shown with the Gold type of heaters; but they may be used 50 with various other types. Referring specifically to the embodiment of the invention illus-

trated in Fig. 1, single heaters A are arranged one under each of the seats B of the car and are connected to each other by wires carried through conduits C, of iron or other suitable material. Where the wires run into or out of the heater, a junction-box is provided, which I designate as a whole by the letter D.

In the single round heaters (shown in Figs 5 to 5) the junction-box is a round casing E, of substantially the same diameter as the heater, adapted to be fastened on the end of the porcelain head F of the heater, so as to form practically an extension thereof. The attachment, for example, may be by means 60 of a carriage-bolt G, Fig. 4, passing through a suitable socket in the head F and thence through an opening in a bridge H, formed in the adjacent end of the junction-box. The end of the bolt G projects into the junction-box and is accessible to permit the application of the clamping-nut J and set-nut K. A sheet L, of asbestos or of similar refractory material, is preferably introduced between the junction-box and the head F of the 65 heater to serve as a fireproof packing. The junction-box has projections a a, which enter recesses a' a', Fig. 5, in the porcelain head F to prevent the heater from turning relatively to the box.

In the heater shown in Fig. 3 the electric connections are made above the central point through which the bolt G passes. The heater shown utilizes two coils, one above the other, supported on rods extending between 70 heads F and F'. Only the uppermost coil is shown. This coil M is supported upon a sinuous insulating-rod N and is connected at one end to a binding-post O and at the opposite end to a return-rod P. The binding-post O and return-rod P project into sockets Q in the outer end of the porcelain head F and are provided with suitable washers and clamping-nuts for clamping the ends of the wires R, which then pass out through the asbestos 75 end plate L and constitute the effective ends of the heater-wires, to which the main or line wires are to be connected.

The junction-box E is provided with sockets for receiving the ends of the conduits C. There may, for example, be a number of sockets S on the end—four in the case shown, Fig. 6—to receive two incoming wires and two outgoing ones and with a socket T on the under side for receiving the end of a conduit U, which extends downward below the floor of the car. Usually the boxes are man-

ufactured with the five sockets described, so that they may be used for making connections to the end heater through a conduit, such as U, Fig. 2, and for making connections between successive intermediate heaters in the manner shown in Fig. 1. The sockets S are of such size as to receive the ends of the conduits C and are provided with shoulders V, which limit the inward movement of the conduits, and with clamping-screws W, Fig. 5, which hold the conduits in position.

The main or line wires X are extended somewhat beyond the ends of the conduits C and are bared, the usual flexible insulation Y being removed, and the ends of the wires X are then twisted or otherwise connected with the ends of the heater-wires R. In order to have access to the interior of the junction-box, a cover-plate Z, Figs. 5 and 6, is provided, fastened by screws a^2 . The removal of the cover-plate opens an entire side of the junction-box and leaves plenty of room for the necessary manipulations. Openings b are provided on the inner end of the junction box for passing the wires R into the box, these openings being separated by the bridge H.

Where the heaters A A' are used in pairs, as in Figs. 7 and 8, the wires lead into the heater A at its inner end, then out of the heater A and into the heater A' at the outer ends of the heaters, and thence out from the inner end of the heater A' in the manner indicated by the arrows. The heaters being arranged close together, one junction-box D is arranged to extend over the adjacent ends of two heaters. The casing c in this case is oblong and is provided on its inner end d with projections e, fitting in suitable sockets in the heads F of the heaters, and with suitable openings for the reception of clamping-bolts G, which, in conjunction with the projections e, hold the heaters in proper position relatively to the box. The inner end of the junction-box has also suitable openings b for the admission of the heater-wires R. For greater accessibility in this case the entire outer end f of the casing is removable, and the wires are let in and out through holes g at the top and bottom of the box, respectively.

The riser-heaters (shown in Figs. 9 to 12) have their porcelain heads F² half-round instead of entirely circular. The wires in this case run in substantially the same direction as the heaters themselves, and the junction-box consists of a frusto-conical casing h, overlapping the end of the porcelain head F² of the heater and having flanges j adapted to be fastened to the riser or other backing, against which the casing k of the heater is fastened. These boxes are open entirely at the end adjacent to the head of the heater, while the opposite end l is provided with openings m, through which the conduits C

are admitted. It will be understood that the connections are made in this case before the junction-boxes are applied. It is not necessary to break off the wires R and make a separate connection thereof with the line-wires. The wires R may run continuously from one of the heaters to the next, constituting, in fact, the line-wires, the only junction to be protected being that of the wires R with the binding-posts of the heater.

Where the heaters A and A' are very close together, as shown in Figs. 11 and 12, the casings h for adjacent heaters may be united into a single cylindrical casing h', which may be simply a trough-shaped piece of sheet metal with suitable flanges j' for fastening it to the backing after the connections between the adjacent heaters have been made.

In the construction shown in Figs. 13 to 15 the truss-plank of the car is indicated at n. A backing-plate o is usually provided to prevent overheating the truss-plank and to deflect the air outward into the car, the backing-plate being faced with asbestos or the like. Porcelain heads F³ are fastened to the backing-plate o and carry the coils and terminal wires R in substantially the same manner as in the previous figures. The outer casing p of the heater may be applied after the connections have been made between the line-wire X and the heater-wire R and is provided with extensions q at the ends lying beyond the porcelain heads E and serving to inclose the junction of the wires, the extensions q of the casing being provided with sockets r for the reception of the ends of the conduits C. The entire casing p, with its extensions, is fastened to the truss-plank by means of flanges s, Fig. 15.

Though I have described with great particularity of detail certain specific embodiments of my invention, yet it is not to be understood therefrom that the invention is limited to the specific embodiments disclosed.

Various modifications in detail and in the arrangement and combination of the parts may be made by those skilled in the art without departure from the invention.

What I claim is—

1. An electric car-heater having a resistance medium interposed between a pair of opposite heads through at least one of which a conducting-wire passes and between which said medium is exposed to the air to heat it, and having a chamber outside of the head through which such wire passes, said chamber constituting a junction-box for inclosing the connection of such wire with the line-wire leading to the heater.

2. An electric car-heater having a resistance medium interposed between a pair of opposite heads through at least one of which a conducting-wire passes and between which said medium is exposed to the air to heat it, in combination with a separate casing form-

- ing a chamber outside of the head through which such wire passes, said chamber constituting a junction-box for inclosing the connection of such wire with the line-wire leading to the heater. 5
3. An electric car-heater having a chamber constituting a junction-box for inclosing the ends of the line-wires leading into the heater, said junction-box having a socket for receiving the end of a conduit inclosing the line-wire outside of the heater. 10
4. The combination with an electric car-heater, of a line-wire and a conduit inclosing the same, and a junction-box receiving the end of said conduit and providing a space between said conduit and the heater and inclosing the junction between the line-wire and the end of the heater-wire. 15
5. A detachable junction-box for an electric heater and having an opening for the passage of a wire and having a hand-hole, and a movable plate covering said hole. 20
6. A detachable junction-box D for an electric heater and having an opening in its end for the passage of a wire and having at its side a hand-hole, and a removable plate Z covering said hole. 25
7. The combination with an electric heater of a junction-box therefor having a pair of openings for receiving a pair of parallel wires, and having also a single opening for receiving a wire entering or departing in a transverse direction to the direction of said parallel wires. 30
8. The combination with an electric heater, of a junction-box D having a bridge H adjacent to the end of the heater, said heater and box being provided reciprocally with means for preventing relative rotative displacement, and means for fastening said bridge to said heater. 35
9. The combination with an electric heater, of a junction-box having a bridge H adjacent to the end of the heater, and fastening means for uniting said bridge to said heater. 40
10. The combination with an electric heater and conduits for the line-wires, of a junction-box inclosing the joint between the wires of the conduits and heater respectively, attached to the heater, and detachably engaging the conduits whereby it may be disconnected from the conduits without displacing them and without disconnecting it from the heater. 45
- In witness whereof I have hereunto signed my name in the presence of two subscribing witnesses. 50
